United States Patent Office

Des. 224,590

Patented Aug. 8, 1972

224,590

CHAIR

Morris F. Fisher, Carmel, Ind., assignor to Mohasco
Industries, Inc., Amsterdam, N.Y.

Filed Dec. 23, 1970, Ser. No. 26,632

Term of patent 14 years

Int. Cl. D6—02

U.S. Cl. D15—1

The figure is a perspective view of a chair embodying my new design. The side not shown is like the side shown while the back of the chair is conventionally plain and unornamented.

I claim:

The ornamental design for a chair, substantially as shown and described.
